J. BECKER

HEATING SYSTEM FOR RETORT COKE OVENS

Filed Sept. 17, 1921

INVENTOR

Julius Becker
BY his ATTORNEY
Clarkson A. Collins

UNITED STATES PATENT OFFICE.

JULIUS BECKER, OF SYRACUSE, NEW YORK, ASSIGNOR TO SEMET-SOLVAY COMPANY, OF SOLVAY, NEW YORK, A CORPORATION OF NEW YORK.

HEATING SYSTEM FOR RETORT COKE OVENS.

Application filed September 17, 1921. Serial No. 501,263.

To all whom it may concern:

Be it known that I, JULIUS BECKER, a citizen of the United States, residing at Syracuse, in the county of Onondaga and 5 State of New York, have invented a new and Improved Heating System for Retort Coke Ovens, of which the following is a specification.

My invention relates particularly to that 10 type of oven in which horizontally disposed heating flues are arranged in two sets on each side of the oven with a division wall between the two sets, and the object of my improvement is to provide a system of flues 15 for the delivery of hot air from a regenerator to the heating flues and the discharge of gases of combustion from the heating flues to the regenerator, which shall insure free and uniform movement of the gases and 20 consequent efficient and uniform coking of the oven charge.

The invention will be best understood by reference to the accompanying drawings, forming a part hereof, Fig. 1 of which 25 shows a vertical cross section through a battery of coke ovens partly broken away to show the heating flues; Fig. 2 shows a vertical cross section through the heating flues, and Fig. 3 is a plan view on the line 3—3 30 of Fig. 1.

Referring to the drawings, A indicates the retort, or coking chamber, on each side of which are located two sets, B, B', of horizontally disposed heating flues, separated by 35 a division wall C, which are supplied with gaseous fuel by burners b, b'.

Below and parallel with each retort are located two regenerators D, D', constructed of checker work brick in the usual manner, 40 and between the regenerators are two air and gas flues E, E', which run lengthwise of the oven block and are arranged to be connected at the end of the oven block with any usual or convenient form 45 of reversing valve (not shown in the drawings) so that they can be connected alternately with the open air and with the chimney stack, as may be required.

The flue E is connected with the regenerator D by an opening, d, and the flue E' 50 is connected with the regenerator D' by an opening d'. From the regenerator D, a flue F, located below the heating flues, leads to a vertically disposed flue G which passes 55 upward through the division wall C' be-

tween the two sets of flues B, B', to a point above the uppermost flue, 1, where it is divided into two branches, H, H', which extend along above the heating flues and are respectively connected, the one, as H, with 60 the uppermost oven flue 1, of the set B, and the other, as H', with the uppermost flue 1, of the set B'.

The lowermost flues 6, 6, of the two sets of heating flues are connected by short passages, f, f, and openings g, g, with a sole flue I, which extends along underneath the retort, A, and from the sole flue I, a passage K leads to the regenerator D'.

In the operation of the oven the air for 70 the support of combustion of the fuel in the heating flues enters through that one of the flues E, E', which is at the time connected with the atmosphere, as E, and passes thence into regenerator D, and from the regenerator by flue F, riser G, and branch flues H, H', to the uppermost flues 1, 1, of the two sets of heating flues. At the same time the gaseous products of combustion pass from the oven flues 6, 6, into the sole 80 flue I, and thence by passage K, to the regenerator D', heating it. From the regenerator, D', the gases pass into the flue E' and thence to the stack. On changing the reversing valve, air enters by flue E', into 85 the regenerator D', and thence by passage K, sole flue I, and passages f, f, to the lowermost flues 6, 6, of the two sets of oven flues. At this time the gases of combustion pass out of the uppermost oven flues, 1, 1, by 90 passages H, H' and thence by passages G and F to regenerator D, and so to flue E, and the chimney stack.

The flue system is duplicated on the two sides of the oven, the heating flues on both 95 sides receiving hot air from and discharging hot gaseous products of combustion into the same regenerator.

My invention affords a simple, efficient and inexpensive form of construction in 100 which a minimum of push is required to remove the heavy gaseous products of combustion from the heating flues and by which a constant and uniform temperature is maintained in the oven chamber.

Having thus described my invention, what I claim as new and desire to secure by Letters Patent is:—

1. In a heating system for retort coke ovens the combination of a coking cham- 110

ber, two sets of horizontally disposed heating flues on each side of said chamber, and two regenerators located below the chamber and parallel thereto, one of said regenerators being connected with the lowermost heating flues on each side of the chamber and the other being connected with the uppermost heating flues on each side of the chamber.

10 2. In a heating system for retort coke ovens the combination with a coking chamber, of two sets of horizontally disposed heating flues, separated by a vertical dividing wall, on each side of said chamber, two

regenerators located below and parallel with 15 the coking chamber, a sole flue located below the chamber, passages connected with one of said regenerators and passing vertically upward through said dividing walls, 20 passages connecting said vertical passages with the uppermost flues of said sets of flues, passages connecting the lowermost flue of each of said sets of flues with the sole flue and a passage connecting the sole flue with the other of said regenerators.

In testimony whereof I affix my signature, this 15th day of September, 1921.

JULIUS BECKER.
